UNITED STATES PATENT OFFICE.

THEODORE A. WILLARD, OF CLEVELAND, OHIO, ASSIGNOR TO WILLARD STORAGE BATTERY COMPANY, OF CLEVELAND, OHIO, A CORPORATION OF WEST VIRGINIA.

STORAGE-BATTERY PLATE.

No. 888,951.

Specification of Letters Patent.

Patented May 26, 1908.

Application filed March 29, 1907. Serial No. 365,341.

To all whom it may concern:

Be it known that I, THEODORE A. WILLARD, a citizen of the United States, residing at Cleveland, in the county of Cuyahoga and State of Ohio, have invented a certain new and useful Storage-Battery Plate, of which the following is a specification.

The principal object of the present invention is to prevent increase of the overall length of a one-piece plate such as is brought about by the growth or expansion due to the formation and use of the plate.

Another object of the invention is to prolong the useful life of the plate.

To these and other ends hereinafter set forth, the invention comprises the improvements to be presently described and finally claimed.

The nature, characteristic features and scope of my invention will be more fully understood from the following description taken in connection with the accompanying drawings forming part hereof and in which

Figure 1, is a side view of a plate embodying features of the invention, and Fig. 2, is a transverse sectional view taken on the line 2—2, of Fig. 1.

The plate consists of a blank all of which is of like metal, or in other words, of a one-piece blank. Upon the opposite faces of the blank there are rows or stripes 1, of ribs with flat spaces or stripes 2, between them. The ribs are shown to project outward beyond the flat parts 2. 3, are holes or openings arranged in the stripes or rows of projecting ribs and they extend clear through the plate. As shown they are of oval form arranged with their longest axes crosswise of the rows of ribs and the openings in one row or stripe of ribs are arranged out of line with the openings in the adjacent stripe or row of ribs. In this way the plate is not weakened. The openings 3, afford space which, by receiving

the growth of the material, prevents an increase of overall length of the plate, and the oppositely disposed sets of ribs are expansively balanced or in other words on each side of the plate the corresponding sets of ribs are so constructed and arranged that in use they expand or tend to grow equally. One, but not the only way of doing this is to make the ribs in each set identical in cross section. Furthermore under these conditions the tendency of plates to buckle is obviated. The ribs and material in the stripes between the openings may grow endwise and more or less fill the openings so that there are not created in the plate undue strains while at the same time the overall length of the plate does not increase and it is not subject to buckling, bending and twisting. In consequence of this the useful life of the plate is materially increased.

What I claim is:

1. A battery plate consisting of a one-piece blank having rows or stripes of projecting ribs alternating with rows or stripes of flat spaces arranged on opposite faces of the plate and having oval openings arranged crosswise of the ribbed stripes and out of alignment with each other, substantially as described.

2. An integral battery plate consisting of a blank having on its opposite faces sets of projecting ribs alternating with unribbed spaces and the oppositely disposed sets of ribs being expansively balanced, and said plate having crosswise openings intermediate intercepting said ribs, substantially as described.

In testimony whereof I have hereunto signed my name in the presence of two witnesses.

THEODORE A. WILLARD.
